INDALECIO NORIEGA, OF MEXICO, MEXICO.

SYNCHRONIC TWIN PHONOGRAPH.

1,271,066.

Specification of Letters Patent. Patented July 2, 1918.

Application filed September 12, 1917. Serial No. 191,091.

To all whom it may concern:

Be it known that I, INDALECIO NORIEGA, a subject of the King of Spain, residing at Mexico city, Federal District, Mexico, have 5 invented certain new and useful Improvements in Synchronic Twin Phonographs, of which the following is a specification.

My invention relates to phonographs and has for its object to provide a double phonograph of synchronistic functions, whereby it is possible to obtain unlimited phonographic reproductions of song, music, speeches, etc., in an uninterrupted manner. This is attained by disposing two synchronically operated phonographs to alternate in the reproduction of the record. Each disk contains only such a portion of the entire record as will fit it, the rest being engraved in pieces on several disks, which when played 20 at successive stages complete the full record, that of course may be of any length.

In the accompanying drawings Figure 1 is a side elevation of the double phonograph, the front of the cabinet being removed as well as the horn. Fig. 2 is a plan view, with part of the turn-table at one side of the instrument, and the top of the cabinet at the other side, removed. Fig. 3 is a top view of the apparatus. Fig. 4 is a diagram 30 of the electrical connections for the twin phonographs.

Referring in detail to the drawings (1) is a motor mounted at the bottom of the cabinet and having a hollow shaft (2) extending horizontally beyond it at both sides where clutches (3^a) and (3^b) are slidably carried.

The clutches are provided with annular grooves into which the resilient stop pins 40 (25) are inserted in order to maintain the clutch in coupling. Through the hollow shaft (2) extends the spindle (4) adapted to slide endwise when pulled by either of the magnets (6) to the cores (5) of which its 45 two extremities are connected.

On the spindle (4) are the disengaging worm gears (7) which mesh with the worm wheels (8) attached to the vertical shafts (9). These shafts pass through the cover 50 of the cabinet on top of which they carry the turntables (10) provided with central pins (16) and eccentric pins (17) the latter of which project vertically in opposite directions beyond the turn tables, the upper portions 55 piercing the disks, while the lower portions constantly touch the contact plate

(18), on which they slide. The screw terminal (19) of each phonograph connects by wire to the magnet (6) at the opposite side of the cabinet.

Supported at the top of the cabinet are the phonograph amplifiers (11) each connected with its respective tone arm (12) and reproducer (13). These amplifiers are curved once and both join at (14) in the bell of the single horn not shown, but which extends horizontally out of the cabinet. Each reproducer (13) has a contact pin (15) and a stylus (24).

In the side of the cabinet are the screw terminals (20), to which the main wires (not shown) lead, these terminals (20) having connected to them conducting wires (likewise omitted) which supply current first to the screw terminals (22) and (23), and next to the motor; and by the screw terminals (21) are connected with the magnets (6) and are electrically connected with the motor circuit.

The parts of both of the twin phonographs are identical, and for clearness of description I shall refer to these parts as "a" when belonging to one side (on the left), and "b" when referring to the parts of the twin phonograph of the opposite side (on the right).

The long compositions or other matter to be reproduced are recorded on a series of disks, so that when disk number 1 has been recorded to its full capacity, then the contact pin (15^a) of the left-hand recorder (13^a) will have reached the eccentric contact pin 17^a which closes the electric circuit whereby the magnet (6^b) of the opposite or right-hand side sets the turntable (10^b) in motion, and the recorder (13^b) immediately starts to engrave on disk number 2 supported thereon. A new disk number 3 is placed on the turntable (10^a) to be engraved by the recorder (13^a) and in this manner a long record, of an opera for instance, is engraved on series of record disks, which will enable the reproduction of the whole record practically without any interruption.

Now for reproducing the stylus (24^b) is set at the beginning of the record groove of disk number 2 and remains inactive until the other stylus (24^a), which is operating on disk number 1, has concluded the reproduction of the record thereon, which happens at the very moment the contact pin (15^a) touches the contact pin (17^a), thereby clos-

- 2
- ing the circuit of the right-hand magnet (6^b), and attracting its core (5^b), the consequence of which is, that the right-hand clutch (3^b) is thrown into gear and transmits motion to the turn table (10^b), at the same time uncoupling the left-hand clutch (3^a). Thus, when the phonograph of the "b" side starts, the motion of the phonograph of the "a" side stops.
- 10 When the instrument is not in use, the motor circuit, which may be controlled by any suitable means, for instance a button switch, is open, and of the two clutches one is coupled and the other uncoupled. In 15 operation, and starting, with the left-hand phonograph, the motor circuit is closed by means of the above-mentioned switch, whereupon the motor commences to drive the shaft 2, the current flowing from the mains 20 through the terminals 20 to the conducting wires connected thereto and thence through the terminals 22 to the motor. The two magnet circuits are in the nature of secondary circuits which are normally open, one 25 or the other of these circuits being closed by the engagement of the respective contact pins (15^a) and (17^a) or (15^b) and (17^b). Assuming that the left-hand clutch (3^a) is coupled, since it is the left-hand phonograph 30 which is to be played first, the rotation of the motor shaft will be transmitted to the left-hand turn-table shaft and the corresponding tone arm (12^a) and sound - box (13^a) will be fed inward in the usual manner.
- 35 When the contact pin (15^a) on the sound box strikes against the corresponding pin (17^a), the circuit including the right-hand magnet (6^b) will be closed, the current flowing from one service terminal (20), which 40 will be assumed to be the lower one in Fig. 4, to the adjacent terminal (22), thence to and through the magnet and its terminals (21^b), by way of the connecting wire or wires, thence to the terminal (19^a), and 45 thence through the contacts (17^a) and (15^a) and the connecting wire or wires between the latter and the terminal (23) back to the other service terminal (20). The closing of this circuit energizes the magnet (6^b), 50 whereupon its core (5^b) is attracted and pulls spindle (4) to the right, the movement of said spindle closing clutch (3^b) and opening clutch (3^a), with the result that the right-hand turn-table starts to rotate and the left-hand turn-table stops. It is understood, of 55 course, that disks have been placed upon both turn-tables, and that the styli of both sound-boxes have been placed in playing position before the operation of the instrument 60 commences, so that the right-hand phonograph will be ready to play the instant that its turn-table starts to rotate. So, after the completion of playing of the record on the left-hand turn-table, that record is removed 65 therefrom and replaced by the next record
- in order, and the corresponding sound-box and tone arm are moved back to position the stylus at the beginning of the record. The same general actions then take place with the right-hand phonograph as have 70 just been described in connection with the left-hand phonograph. That is to say, the tone arm (12^b) and sound-box (13^b) swing inward as playing continues, until the contacts (15^b) and (17^b) engage, whereupon 75 the other magnet circuit containing the magnet (6^a) is closed. The closing of this circuit energizes said magnet (6^a) which, in turn, attracts its core (5^a), the movement of the latter pulling spindle (4) to the left to close 80 clutch (3^a) and upon clutch (3^b). The motor shaft then proceeds to rotate the left-hand turn-table shaft, the motion of the right-hand shaft ceasing. When the last-mentioned circuit is closed by the engagement 85 of the contacts (15^b) and (17^b), current passes from one service terminal (20) to and through magnet (6^a) and its terminals (21^a), thence through the connecting wire or wires to the terminal (19^b), and thence through 90 the contacts (17^b) and (15^b) and connecting wire or wires and the terminal (23) to the other service terminal (20).
- It is seen that the alternating operation of the two reproducers is automatic, and 95 there will be no interruptions to the reproduction caused by changing record disks, as is the case with phonographs hitherto known.
- Having thus described my invention what I claim is:
1. In a sound recording and reproducing apparatus, the combination, with a pair of record supports, a tone arm movable across each support, and a shaft whereon each support is mounted; of a motor; and an electrical system for driving said shafts in alternation from said motor, comprising alternately-acting means for determining the shaft to be driven, a pair of magnets connected to actuate said determining means, 100 a pair of normally-open magnet circuits, a pair of stationary contact plates, one in each circuit, located beneath the record supports, a contact pin mounted in each record support and extending vertically above and below the same, the lower end of each pin slidably engaging the adjacent contact plate, and a contact member in each circuit and connected to move with one of said tone arms so as to engage the upper end of the 105 adjacent contact pin at the conclusion of playing of a record on the corresponding support.
2. In a sound-recording and reproducing apparatus, the combination, with a pair of record supports, a tone arm movable across each support, and a shaft whereon each support is mounted; of a motor; a hollow driving shaft associated therewith; an end-wise movable spindle mounted in said hol- 110
- 115 120 125 130

- low shaft to rotate therewith and projecting beyond the same at opposite ends; a driving connection between each end of said spindle and the adjacent record support shaft, each driving connection including a device which is alternately coupled and uncoupled by the movements of said spindle in one direction or the other; and means for automatically effecting the endwise movement of said spindle at the conclusion of the playing movement of each tone arm across the record on the corresponding support; thereby to uncouple the driving connection between said spindle and the corresponding record support shaft and simultaneously couple the driving connection between the spindle and the other record support shaft.
3. In a sound-recording and reproducing apparatus, the combination, with a pair of record supports, a tone arm movable across each support, and a shaft whereon each support is mounted; of a motor; a hollow driving shaft associated therewith; an endwise movable spindle mounted in said hollow shaft to rotate therewith and projecting beyond the same at opposite ends; a driving connection between each end of said spindle and the adjacent record support shaft, each driving connection including a device which is alternately coupled and uncoupled by the movements of said spindle in one direction or the other; and an electrical system for automatically effecting the endwise movement of said spindle at the conclusion of the playing movement of each tone arm across the record on the corresponding support, thereby to uncouple the driving connection between said spindle and the corresponding record support shaft and simultaneously couple the driving connection between the spindle and the other record support shaft; said system comprising a pair of magnets connected with the opposite ends of said spindle, a pair of magnet circuits, and circuit-closing means for each circuit embodying a pair of cooperating contacts, one connected to move with the record support, and the other to move with the tone arm into engagement with the first-named contact.
- In testimony whereof I have affixed my signature.
- INDALECIO NORIEGA.
